BRUSH RIGGING

Wayne J. Morrill, Fort Wayne, Ind., assignor to
General Electric Company, a corporation of
New York

Application December 23, 1942, Serial No. 469,861

11 Claims. (Cl. 171—324)

My invention relates to brush riggings such as are used in connection with dynamo-electric machine current collectors.

An object of my invention is to provide an improved and simplified brush rigging.

Another object of my invention is to provide an improved brush rigging in which the brush and brush holder move as a unit relative to a current collector and the contact surface of the brush remains substantially the same for all conditions of wear of the brush.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, Fig. 1 is an exploded perspective view of an embodiment of my improved brush rigging; Fig. 2 is a side elevational view, partly in section, illustrating an assembly of the brush rigging shown in Fig. 1; Fig. 3 is an exploded perspective view of a brush rigging provided with another embodiment of my invention; Fig. 4 is an assembled perspective view of the brush rigging shown in Fig. 3; and Fig. 5 is a side elevational view, partly in section, of the brush rigging shown in Figs. 3 and 4.

Referring to the drawing, I have shown in Figs. 1 and 2 a brush rigging which includes a contact brush member formed of a graphitic element 10 having a wearing contact lower portion with substantially parallel curved opposite sides 11 and 12 formed on the same center of curvature. The contact brush element 10 is formed with a brush holder engaging portion 13 having opposite sides, one of which is formed by the side 11 and the other of which is formed by a tapered side 14 extending at an angle to the sides 11 and 12 providing a substantially wedge shape to the end brush holder engaging brush portion 13. A metal sheath 15 is arranged over the brush holder engaging portion of the brush member and is secured to the graphitic portion of the brush 10 by a suitable rivet 16. This brush member is adapted to be supported by a brush holder and resiliently biased into contact with a current collector 17. The brush holder is provided with sides 18 which are held together by a transversely extending plate 19 having fastening tabs 20 which extend through openings formed in the sides 18 and which are upset to provide rivet heads securing together the sides 18 and the transverse plate 19.

Each of the sides 18 of the brush holder is formed with an inturned brush engaging end element 21. These elements 21 are arranged to engage the brush at transversely spaced apart points on one side of the brush member metal sheath 15. The transverse plate 19 of the brush holder is formed with spaced apart projections 22 and 23 adjacent the upper and lower ends thereof respectively, and these projections are formed on the plate 19 transversely thereof intermediate the brush engaging elements 21 and are spaced longitudinally above and below the elements 21 to provide for engagement of the brush member sheath 15 on the side thereof opposite the side 14 to provide brush engaging points spaced apart longitudinally of the brush member and spaced transversely intermediate the points of engagement of the brush with the elements 21 for wedging the brush member between the engaging elements on the opposite sides thereof. This provides for a rigid support of the brush in the brush holder and prevents any relative movement therebetween. The brush member and the brush holder are adapted to be biased resiliently as a unit towards the current collector 17 by a resilient coil spring 24 which is provided with an end portion 25 hooked over a stationary pin 26 and another end portion 27 in engagement with an inturned end portion 28 of the transverse plate 19. The brush holder is pivotally supported on a spindle 29 adapted to extend through holes 30 in the brush holder sides 18 and is provided with a head 31 for holding the brush holder on the spindle. The end of the spindle away from the head 31 is threaded to provide for securing it to a suitable bracket for pivotally supporting the brush and brush holder about an axis 32 of the spindle 29 which lies in a plane indicated by the line 33 which is substantially tangent to the current collector 17 at the center of the contact of the brush member with the current collector. The center of curvature of the sides 11 and 12 of the brush element 10 coincides substantially with the axis 32 of the pivotal support for the brush holder. With this construction, the curved contact face 34 of the brush element 10 remains substantially the same for all conditions of wear of the brush 10. This also minimizes the tendency for the brush 10 to "toe" or "heel" with different directions of rotation of the current collector 17. It is desirable that the pressure on the brush element 10 should be substantially the same for both directions of rotation in order further to minimize the tendency to "toe" or "heel" under different directions of rotation of the current col-

lector 17. This uniform pressure can be further assured by arranging the points of engagement of the elements 21 with the metal sheath 15 nearer to the lower point of engagement 23 than to the upper point of engagement 22 of the plate 19. With this type construction, a pigtail connection can be made directly to the brush holder, if desired, or to the metal sheath 15, and the simple brush member construction minimizes breakage of these member which occurs with conventional constructions using screws or other pressure devices for securing the brush members to the brush holders.

In Figs. 3, 4, and 5, I have shown another embodiment of my invention wherein a brush member is provided having a graphitic contact element 35 with curved opposite sides 36 and 37 formed on substantially the same center of curvature. A metal sheath or cap 38 is secured to the upper end of the contact element 35 by a pair of rivets 39 and a pigtail 40 is secured to the cap 38 and adapted to provide an electrical connection to a suitable source of electrical power supply. The brush member is adapted to be biased towards a current collector 41 by a brush holder in which it is rigidly secured without the use of screws or similar pressure clamping devices. This brush holder includes a pair of elements adapted to engage opposite sides of the brush member at spaced apart points for holding the brush in the brush holder. One of these elements is formed as a sheet metal stamping having a side 42 with an enlarged pivotal supporting opening 43 in an end thereof integrally formed with a transverse face portion 44 and an opposite side portion 45. The face portion 44 is formed with a pair of transversely spaced apart inwardly projecting brush engaging sections 46 which are adapted to engage the outer curved side of the brush member cap 38 which extends over the side 37 of the brush contact element and is also formed with inturned end tabs 47 at the upper edge thereof which are arranged to engage the upper surface 48 of the brush member cap 38. The brush member is adapted to be held in the brush holder between the engaging sections 46 and another element formed of a sheet metal stamping having a transverse plate portion 49 with a brush engaging section 50 which extends longitudinally of the brush and projects outwardly from the plate 49 to engage the inner curved side of the brush cap 38 over the curved brush side 36 at a point transversely intermediate the point of engagement of the brush holder sections 46 and the brush for wedging the brush member between the engaging elements on the opposite sides thereof. The plate 49 is arranged between sides 51 and pivotally supported by a pivot pin 52 which extends through openings 53 in the sides 51 and also through the opening 43 of the side 42 of the other brush holder element. The two brush holder elements are connected together for guided limited relative movement by a pin 54 which extends through openings 55 formed in the sides 51 of one brush holder element and through slots 56 formed in the sides 42 and 45 of the other brush holder element. The slots 56 extend angularly relatively to a line drawn between the holes 53 and 55 in the sides 51 of the other brush holder element such that relative pivotal movement between the two elements causes their brush engaging surfaces 46 and 50 to move toward or away from each other. In order to provide for this relative

movement, the opening 43 in the side 42 of one of the elements is formed larger than the pivotal supporting pin 52. The brush engaging surfaces of the two elements are adapted to be biased toward each other and the brush and brush holder biased toward the current collector 41 by a resilient coil spring 57 arranged about the pivot pin 52 and provided with an end portion 58 hooked over a stationary pin 59 and another end portion 60 thereof arranged in engagement with an upper plate portion 61 and a tab 62 extending between the sides 51 of the outer brush holder element. As in the construction shown in Figs. 1 and 2, the axis of the supporting pin 52 for the brush holder lies in a plane indicated by the line 63 substantially tangent to the center of contact between the brush member 35 and the current collector 41 to insure substantially the same curvature of the brush contact face 64 for all conditions of wear of the brush element 35. With this arrangement, the biasing spring 57 provides for rigidly holding the brush member in the brush holder by a wedging action between the transversely spaced apart engaging surfaces of the sections 46 and 50 of the brush holder with the cap 38 of the brush member and also for biasing of the brush holder and brush member as a unit towards the current collector 41. A lifting tab 65 is formed on the face 44 of the brush holder intermediate the tabs 47 for raising the brush holder to replace or inspect the brush member.

While I have illustrated and described particular embodiments of my invention, modifications thereof will occur to those skilled in the art. I desire it to be understood, therefore, that my invention is not to be limited to the particular arrangements disclosed, and I intend in the appended claims to cover all modifications which do not depart from the spirit and scope of my invention.

What I claim as new and desire to secure by Letters Patent of the United States is:

1. A brush rigging for a brush member including means including a pivotally supported brush holder having elements adapted to engage one side of said brush adjacent opposite edges of said brush member at transversely spaced apart points for holding said brush member in said brush holder, means for engaging the opposite side of said brush intermediate said transversely spaced apart points, said last-mentioned means and said brush engaging elements of said brush holder and said opposite sides of said brush member being arranged relatively to each other to provide for wedging of said brush member between said engaging elements on opposite sides of said brush member, and resilient means for biasing said brush holder and brush member as a unit toward a current collector and thereby increasing said wedging action between said engaging elements and said brush member sides.

2. A brush rigging for a brush member including means including a pivotally supported brush holder having elements adapted to engage one side of said brush adjacent opposite edges of said brush member at transversely spaced apart points for holding said brush member in said brush holder, means for engaging the opposite side of said brush intermediate said transversely spaced apart points, said last-mentioned means and said brush engaging elements of said brush holder and said opposite sides of said brush member being arranged relatively to each other to provide for wedging of said brush member between said engaging elements on opposite sides of said

brush member, and means for biasing said brush holder and brush member toward a current collector.

3. A brush rigging for a brush member including means including a pivotally supported brush holder having elements adapted to engage one side of said brush member at transversely spaced apart points and the opposite side of said brush member at longitudinally spaced apart points intermediate said first-mentioned points for holding said brush member in said brush holder, said brush engaging elements of said brush holder and said opposite sides of said brush member being arranged relatively to each other to provide for wedging of said brush member between said engaging elements on opposite sides of said brush member, and means for biasing said brush holder and said brush member toward a current collector.

4. A brush rigging for a brush member including means including a pivotally supported brush holder having elements adapted to engage one side of said brush member at transversely spaced apart points and the opposite side intermediate said first-mentioned points for holding said brush member in said brush holder, said brush engaging elements of said brush holder and said opposite sides of said brush member being arranged relatively to each other to provide for wedging of said brush member between said engaging elements on opposite sides of said brush member, and means for biasing said brush holder and said brush member toward a current collector and thereby increasing said wedging action between said engaging elements and said brush member sides.

5. A brush rigging for a brush member including means including a pivotally supported brush holder having elements adapted to engage opposite sides of said brush member at transversely and longitudinally spaced apart points for holding said brush member in said brush holder, said brush engaging elements of said brush holder and said opposite sides of said brush member being arranged relatively to each other to provide for wedging of said brush member between said engaging elements on opposite sides of said brush member, and resilient spring means for biasing said brush holder and said brush member toward a current collector and thereby increasing said wedging action between said engaging elements and said brush member sides.

6. A brush rigging for a brush member including means including a pivotally supported brush holder having an element with a pair of projecting engaging sections adapted to engage one side of said brush at transversely spaced apart points, a second element pivotally supported relatively to said first-mentioned element having a projecting engaging section adapted to engage the opposite side of said brush member intermediate said first-mentioned points, means for connecting together said brush engaging elements of said brush holder for guided relative movement for providing for varying the distance between said projecting engaging sections for wedging of said brush member between said engaging elements on opposite sides of said brush member, and means for biasing said second element relatively to said first-mentioned element into wedging engagement with said brush member.

7. A brush rigging for a dynamo-electric machine including a brush member, means including a pivotally supported brush holder having elements adapted to engage one side of said brush

member at transversely spaced apart points and the opposite side of said brush member at longitudinally spaced apart points intermediate said first-mentioned points for holding said brush member in said brush holder with a current collector contact portion of said brush member projecting from one side of said brush holder, said transversely spaced points being arranged nearer one of said longitudinally spaced points adjacent said brush projecting side of said brush holder to provide substantially equal pressure on said brush member for both directions of rotation of the dynamo-electric machine, and means for biasing said brush holder and said brush member toward a current collector.

8. A brush rigging for a brush member including means including a pivotally supported brush holder having elements adapted to engage one side of said brush member at transversely spaced apart points and the opposite side of said brush member at longitudinally spaced apart points intermediate said first-mentioned points and spaced longitudinally therefrom for holding said brush member in said brush holder with a current collector contact portion of said brush member projecting from one side of said brush holder, said brush engaging elements of said brush holder and said opposite sides of said brush member being arranged relatively to each other to provide for wedging of said brush member between said engaging elements on opposite sides of said brush member, and resilient spring means for biasing said brush holder and said brush member toward a current collector and thereby increasing said wedging action between said engaging elements and said brush member sides.

9. A brush rigging for a brush member including means including a pivotally supported brush holder having elements adapted to engage one side of said brush adjacent opposite edges of said brush member at spaced apart points for holding said brush member in said brush holder, means for engaging the opposite side of said brush intermediate said transversely spaced apart points, said last-mentioned means and said brush engaging elements of said brush holder and said opposite sides of said brush member being arranged relatively to each other to provide for wedging of said brush member between said engaging elements on opposite sides of said brush member, resilient means for biasing said brush holder and brush member as a unit toward a current collector and thereby increasing said wedging action between said engaging elements and said brush member sides, and means having the center line thereof in a plane tangent to the current collector at substantially the center of the contact of said brush member and the current collector for pivotally supporting said brush holder.

10. A brush rigging for a brush member including means including a pivotally supported brush holder having an element with a pair of projecting engaging sections adapted to engage one side of said brush at transversely spaced apart points and elements arranged to engage the top of the brush member, a second element pivotally supported relatively to said first-mentioned element having a projecting engaging section adapted to engage the opposite side of said brush member intermediate said first-mentioned points for holding said brush member in said brush holder, means for connecting together said brush engaging elements of said brush holder for guided limited relative movement for pro-

viding for varying the distance between said projecting engaging sections for wedging of said brush member between said engaging elements on opposite sides of said brush member, and resilient means for biasing said second element relatively to said first-mentioned element into wedging engagement with said brush member and for biasing said brush holder and brush member as a unit toward a current collector and thereby increasing said wedging action between said engaging elements and said brush member sides.

11. A brush rigging for a dynamo-electric machine including a brush member, means including a pivotally supported brush holder having elements adapted to engage one side of said brush member at transversely spaced apart points and the opposite side of said brush member at longitudinally spaced apart points intermediate said first-mentioned points and spaced longitudinally therefrom for holding said brush member in said

brush holder with a current collector contact portion of said brush member projecting from one side of said brush holder, said transversely spaced points being arranged nearer one of said 5 longitudinally spaced points adjacent said brush projecting side of said brush holder to provide substantially equal pressure on said brush member for both directions of rotation of the dynamo-electric machine, said brush engaging elements of 10 said brush holder and said opposite sides of said brush member being arranged relatively to each other to provide for wedging of said brush member between said engaging elements on opposite sides of said brush member, and resilient spring 15 means for biasing said brush holder and said brush member toward a current collector and thereby increasing said wedging action between said engaging elements and said brush member sides.

WAYNE J. MORRILL.
